C. E. DULL,
HEADLIGHT.

APPLICATION FILED SEPT. 22, 1921.

1,419,449.

Patented June 13, 1922.

UNITED STATES PATENT OFFICE.

CURTIS E. DULL, OF OHIO CITY, OHIO.

HEADLIGHT.

1,419,449.

Specification of Letters Patent. Patented June 13, 1922.

Application filed September 22, 1921. Serial No. 502,371.

To all whom it may concern:

Be it known that I, CURTIS E. DULL, a citizen of the United States, residing at Ohio City, in the county of Van Wert and 5 State of Ohio, have invented a new and useful Headlight, of which the following is a specification.

This invention aims to provide a simple means whereby an operator, at will may extinguish the main light of an automobile, and turn on an auxiliary lamp, the auxiliary lamp being so shielded and protected as to cast its rays downwardly upon the roadway, the end in view being to avoid blinding of 15 approaching pedestrians, and the drivers of approaching vehicles.

It is within the province of the disclosure to improve generally and to enhance the utility of devices of that type to which the 20 invention appertains.

With the above and other objects in view, which will appear as the description proceeds, the invention resides in the combination and arrangement of parts and in the 25 details of construction hereinafter described and claimed, it being understood that, within the scope of what is claimed, changes in the precise embodiment of the invention shown can be made without departing from 30 the spirit of the invention.

In the accompanying drawings:

Figure 1 shows in vertical section, a device constructed in accordance with the invention, parts appearing in elevation; and 35 Figure 2 is a diagram showing the circuits.

In carrying out the invention there is provided a support, denoted generally by the numeral 1, and including a pedestal 2 whereon is mounted a main casing 3 carrying a 40 reflector 4 and a lens 5 of any desired construction. A socket 6 is mounted in the main casing 1 and in the reflector 4 and carries an electric lamp 7.

A hood 8 is provided, the same including a 45 rear wall 9, side walls 10 connected thereto, a downwardly and rearwardly inclined top 11 connected to the upper edge of the rear wall 9, and a downwardly and forwardly inclined front wall 12 connected to the side 50 walls 10 and to the top 11, the rear wall 9 having a flange 14 connected by a securing element 15 to the main casing 3. The rear wall 9 of the hood 8 is provided with a socket 16 wherein an electric lamp 17 is 55 mounted, the lamp being disposed within the

hood 8. The entire inner surface of the hood, or such portions thereof as may be desired, may be coated to form a reflector.

The lamps 7 and 17 may be wired up in various ways. Thus, a conductor 20 may 60 lead from one side of the lamp 17 to a ground indicated at 21, a conductor 22 leading from the other side of the lamp 17 to a switch point 23. Similarly, a conductor 24 may lead from one side of the lamp 7 to a 65 ground 25, a conductor 26 leading from the other side of the lamp 7 to a switch point 27. The numeral 28 denotes a battery or other source of electrical energy, a conductor 29 leading from one side of the battery to a 70 ground 30. From the other side of the battery, a conductor 31 leads to a switch 32, adapted to cooperate with the switch points 23 and 27. When the switch 32 cooperates with the switch point 27, the lamp 7 will be 75 lighted, whereas, when the switch 32 cooperates with the switch point 23, the lamp 17 will be lighted. Either lamp, therefore, may be lighted or extinguished at the will of an operator. When the lamp 7 is lighted, 80 the rays will be projected forwardly, in the usual way. When a vehicle or pedestrian approaches, the lamp 7 may be extinguished and the lamp 17 may be lighted, whereupon the rays from the lamp 17 will be projected 85 downwardly toward the ground, it being practically impossible to blind or confuse a pedestrian or the driver of an approaching vehicle.

A lens 75 may be placed in the hood 8, the 90 lens being located in any desired position.

What is claimed is:

The combination with an automobile headlight including a main casing and a front lens, of a hood mounted on top of said 95 casing and comprising a front wall abruptly inclined downwardly and forwardly and overhanging the upper portion of said lens, a wall extending downwardly and rearwardly from the upper end of said front 100 wall, and an upright rear wall merging at its upper end into said second mentioned wall, and a lamp carried by said rear wall.

In testimony that I claim the foregoing as my own, I have hereto affixed my signature 105 in the presence of two witnesses.

CURTIS E. DULL.

Witnesses:

SUMNER C. SHAFFER,
E. F. SISLER.
